METHOD OF HEATING FLUIDS

Lev A. Mekler, Chicago, Ill., assignor, by mesne assignments, to Universal Oil Products Company, Chicago, Ill., a corporation of Delaware

Application December 26, 1931, Serial No. 583,341

Renewed November 10, 1938

1 Claim. (Cl. 196—47)

This invention relates to the heating of fluids and particularly refers to an improved method of heating hydrocarbon oils to the relatively high temperatures required for their conversion.

Many plants employed in the conversion of hydrocarbon oils and built prior to the advent of modern radiant heating methods still employ furnaces utilizing primarily convection heat to raise the oil to the desired conversion temperature. Among other things I have found that many of these furnaces may be easily converted into more efficient heating units, employing the more modern methods of combination radiant and convection heating, by adding, in addition to the existing bank of convection tubes, a row of radiant tubes in the upper portion of the furnace along the roof and along a portion of the walls and by adding a row of radiant floor tubes along the floor of the combustion zone of the furnace. Preferably the old firing arrangement is changed and the improved furnace is fired through one or a plurality of firing tunnels extending into a side of the furnace and having air inlet ducts substantially surrounding or adjacent the firing compartment thereof.

In its specific embodiment the present invention comprises an improved form of furnace for heating fluids having a combustion zone, means for supplying combustible materials to said combustion zone, a convection heating zone, a bridge wall separating said combustion zone from said convection heating zone, fluid conduits disposed along the floor of said combustion zone receiving substantially radiant heat, fluid conduits disposed along the roof and upper portion of the walls of the furnace to receive substantially radiant heat and fluid conduits disposed within said convection heating zone to receive substantially convection heat.

The arrangement of the heating element, i. e., the conduit through which the fluid is passed during heating, as provided by the apparatus of the invention, is especially well adapted to a flow of fluid which results in an improved heating method and which is especially advantageous in heating hydrocarbon oil to the relatively high temperatures utilized in their conversion or cracking. This method comprises subjecting the oil, during the initial stages of its heating, to a relatively high rate of heating to bring it quickly to a conversion temperature, thence subjecting it to continued heating at a somewhat slower rate and finally again subjecting the oil to a relatively rapid rate of heating to bring it to the maximum temperature employed substantially at the out-

let from the heating element. This may be accomplished in the apparatus of the present invention by passing the oil first through the floor bank of radiant tubes, thence through the convection bank of tubes, preferably countercurrent to the flow of combustion gases and finally through the radiant bank of tubes disposed along the roof and sides of the furnace.

The attached diagrammatic drawing illustrates one form of apparatus for carrying out the method of the present invention. Figure 1 is a cross-sectional elevation of the furnace. Figure 2 illustrates diagrammatically the preferred flow of fluid through the heating element of the furnace illustrated in Figure 1. Figure 3 illustrates the general form of heating curve obtainable by employment of the improved heating means illustrated in Figures 1 and 2.

Referring now particularly to Figure 1, the side walls are indicated at 1 and 2, the roof is indicated at 3 and the floor of the combustion zone 4 is indicated at 5. A bridge wall 6 separates combustion zone 4 from convection heating zone 7.

One or a plurality of firing tunnels 8, disposed along side wall 1 of the furnace, furnish means of supplying combustible materials to combustion zone 4. Any suitable fuel such as, for example, oil, pulverized solid fuel, gas or the like, may be introduced through any suitable burner arrangement, not shown, to firing compartment 9, of tunnel 8. Ducts 10 and 11, adjacent firing compartment 9, serve as a means of introducing air, steam or both to the combustion zone of the furnace, the admission of such materials being regulated by dampers 12.

The combustion gases pass upward through combustion zone 4 over bridge-wall 6, downward through convection heating zone 7 and out of the furnace to a stack, not shown, through flue 13.

A row or bank 14 of tubes 15, preferably connected at their ends in series by suitable return bends, headers or other well known means not illustrated, is disposed along the floor 5 of combustion zone 4. Preferably radiant bank 14 is depressed below the level of firing compartment 9 sufficiently to prevent any substantial direct impingement of flame upon the tubes. A radiant bank or row 16 of tubes 15 is disposed along the upper portion of the furnace, adjacent roof 3 and walls 1 and 2. That portion of bank 16 adjacent wall 1 of the furnace may, if desired, be recessed, as illustrated in the drawing, to substantially prevent flame impingement against the tubes. A convection bank 17 of tubes 15 is disposed within

convection heating zone 7 of the furnace, being separated from combustion zone 4 by bridge wall 6. The tubes of radiant bank 16 and convection bank 17 are also preferably connected in series, 5 as already mentioned in connection with radiant bank 14. Radiant heating banks 14 and 16 receive substantially radiant heat from the hot combustion gases and from the heated refractory walls of the furnace while convection bank 17 10 receives substantially convection heat from the somewhat cooler combustion gases passing downward through convection zone 7 around the tubes of said convection bank.

It will be apparent from the drawing, that the 15 tubes of the radiant floor bank 14 are subjected to more severe conditions than the tubes of the other heating banks in the furnace and unless special provision is made for their protection they are susceptible to overheating and consequent damage. The flow of fluid through the 20 heating elements of the furnace which comprises, in part, introducing the relatively cold fluid to be heated, first into the radiant floor bank 14, serves a two-fold purpose. First it provides a means of rapidly bringing the oil to a 25 conversion temperature and, second, by virtue of the relatively cool condition of the oil entering this bank of tubes, said tubes are protected against such overheating as might result if the 30 oil were introduced thereto at a higher temperature, by having first passed through another portion of the heating element.

Referring now to Figure 2 which diagrammatically illustrates the preferred flow of fluid 35 through the heating elements of a furnace such as illustrated in Figure 1. The radiant bank of floor tubes is again indicated at 14, the convection bank is indicated at 17 and the radiant roof and wall bank at 16. The oil to be treated is 40 introduced through line 18 into the first tube of radiant floor bank 14, passing through the succeeding tubes of this bank in series, thence transferring through line 19, preferably located outside the heating zone, to the lower row of 45 tubes of convection bank 17, passing through the succeeding tubes of this bank in series, transferring thence through line 20, which is also preferably located outside the heating zone, to the lower tube of that portion of radiant bank 50 16, located along the upper portion of wall 2 (indicated in Figure 1) of the furnace, passing thence through the succeeding tubes of radiant bank 16 in series and out of the furnace through line 21, being discharged from the lower tube of 55 that portion of radiant bank 16, located along the upper portion of wall 1 (indicated in Figure 1) of the furnace.

Figure 3, as already stated, indicates the general type of heating curve which may be obtained 60 by utilizing the form of furnace illustrated in

Figure 1 and a flow of fluid through the fluid conduit of this furnace, as illustrated in Figure 2. It will be noted from the heating curve and by comparison of this curve with the flow diagram of Figure 2 that the oil is first heated in 5 the radiant floor bank 14 at a relatively high rate, that the temperature obtained in this zone is gradually increased at a slower rate of heating in convection bank 17 and is thence again subjected to a relatively rapid rate of heating in 10 radiant bank 16, discharging from this zone at the maximum temperature attained in the furnace. Those conversant with the cracking art will appreciate the advantages of this type of 15 heating curve in the conversion of many types of oils. Its primary advantages reside in the fact that the oil may be first rapidly raised to a relatively mild conversion temperature, may be thence maintained at a gradually increasing but relatively mild conversion temperature for an extended period of time and may be thence rapidly brought to the maximum conversion temperature desired. This procedure not only minimizes local overheating of the oil with consequent excessive 20 gas and coke formation but also serves as a 25 means of protecting that portion of the fluid conduit which is subjected to the most severe heating conditions by feeding the oil therethrough while said oil is still relatively cool.

It will be understood that the invention is not 30 limited to the particular flow of fluid illustrated in Figure 2, nor to the specific form of furnace illustrated in Figure 1, nor to the type of heating curve indicated in Figure 3, as the principles involved may be accomplished in modified forms 35 of apparatus and under different heating conditions which do not depart from the scope of the invention.

I claim as my invention:

In the heating of hydrocarbon oils to cracking 40 temperature in furnaces having a pair of side walls, a floor and a roof and a bridge wall dividing the furnace into a convection heating zone and a radiant heating zone, the method which comprises firing the furnace adjacent the lower 45 portion of the radiant zone and passing resultant combustion gases through the convection zone, passing the oil initially through tubes adjacent the floor to raise it quickly to mild cracking temperature at a relatively high rate of heating, 50 thence passing the oil through the convection zone to subject it to continued heating at a lower rate of heating, and then raising the oil to maximum cracking temperature under a relatively high rate of heating by passing it through tubes 55 adjacent the side wall nearer the convection zone, then through tubes adjacent the roof and finally through wall tubes on the firing side of the furnace.
